INDEXING DEVICE

John C. Ehrlich, Brooklyn, N. Y.

Application October 30, 1937, Serial No. 171,835

4 Claims. (Cl. 116—121)

This invention relates to bottle caps or stoppers in which an adjustable index is embodied in the cap and it relates in general to adjustable indexing devices. A particular use of the invention is in connection with medicine bottles where the contents are to be used at specified intervals and the adjustable index is so arranged that it may be set to show when the next dose is to be taken.

An object of the invention is to provide a bottle or container cap with an adjustable index, that is readily adjusted, that is comparatively inexpensive to make, that is sanitary and that may be embodied in a popular form of bottle cap. Another object of the invention is to provide a bottle cap with an indexing member to register with index characters on the body of the cap and that is provided with means for retaining the index member in the adjusted position. Other objects of the invention will be more particularly understood from the following specification and the accompanying drawing, showing a variety of applications of the invention, and in which:

Fig. 1 is a top plan view of a bottle cap embodying the invention in which a ball moving in an annular groove in the cap is used for the indexing member;

Fig. 2 is an elevation on line 2—2, Fig. 1;

Fig. 3 is a perspective view of a bottle stopper having a dropper centered therein and a ball type of indicator located in a groove surrounding the stopper;

Fig. 4 is a developed sectional view of the groove in Figs. 1, 2 or 5, showing the corrugations for retaining the ball in position, and

Fig. 5 is a sectional elevation of a modified form of Fig. 1.

This invention is illustrated as applied to bottle stoppers and particularly of the type which are made from molded plastics and screw on the neck of the bottle to form a closure. The top of the cap is provided with an annular row of suitable indexing characters and an annular undercut groove in which the indexing member is located and adjusted to register with the characters. The groove is corrugated either on the bottom or on the sides and the corrugations are located to correspond with the indexing characters of the cap. These corrugations engage the indexing member and hold it in place.

Where low cost is desired, the indexing member may be a ball which is placed in the undercut groove in the cap or body of the device with a portion less than its height or diameter projecting above the surface of the body so that it may readily be rolled along the groove opposite

the index character desired. For the purpose of inserting a relatively large ball in the groove a portion of the wall of the groove may be reduced in cross section so as to yield to the pressure of the ball when it is inserted.

In the drawing, 11 is the body of the cap or stopper which fits to the neck of the bottle by the screw indicated at 16.

In Figs. 1 and 2 the ball 33 is rotated in the annular groove 31 over the corrugations 32 which are located with reference to the indexing characters 14 and 15. The groove 31 is undercut on both sides as indicated at c and c' and is deep enough to engage more than one-half of the sphere. The projecting part of the ball enables it to be easily moved over the corrugations to the position desired and this position points out the character required. Balls for this purpose may be made from phenolic plastics or similar material, or they may be metallic balls. It is found in practice that there is sufficient yield to a substance like Bakelite to permit the metallic ball to be forced into the groove wherein it is retained in use by the yieldable character of the plastic. However, for larger balls it may be desirable to secure a better grip on the ball and for this purpose a portion of the wall of the groove is isolated as indicated by the gap 34, isolating the section 35 so that this portion becomes resilient for the purpose of yielding to the pressure of an oversized ball as it is inserted in the groove.

It is common practice in moulding Bakelite plastics to strip the mould before it cools, this enables the mould to be removed from the undercut groove 31 without injury to the cap. These balls are fairly uniform in diameter and in practice it is found that a ball of substantially three thirty-seconds inch in diameter can be easily forced into a groove the entrance of which is approximately .006 inch smaller than the diameter of the ball. This ball is retained in the groove and can readily be moved along the groove.

In Fig. 3 the bottle stopper 11 is provided with the row of indexing characters at 36 near the top and with the annular groove 31 for the ball 33 which surrounds the central portion 37 of the gap and through which the dropper may be inserted. It should be noted that in this figure and in the other illustrations the movable part of the indexing system is located on the top of the cap and is substantially protected so that as the sides of the cap are gripped to unscrew it from the bottle, there is no likelihood of displacing the index.

The construction in Fig. 5 corresponds with

Fig. 2 except that the annular groove 39 is circular and is larger than a semi-circle in diameter so as to grip the ball 33. The corrugations 40 in this construction are also circular in shape.

- 5 The invention may be applied in any of the forms illustrated or the construction in these forms may be combined to provide a unitary article. In each case the invention comprises two pieces, one of which is the body of the device 10 and the other is the indexing member adjustably positioned on the body. The use of the ball indicator in the groove in the cap has several important advantages: The manufacture is reduced to the cap and the ball, additional parts 15 being eliminated so that it can be supplied at a nominal cost over the plain cap. The ball is exposed where it projects from the groove and when made of metal having a different color from the plastic of the cap it can readily be seen and the indication read. The ball is free to 20 rotate in the groove so that it has rolling friction only and is not likely to jam or to be ejected in the operation of moving it. The ball is a perfectly balanced sphere, it cannot be jarred out 25 of the groove by the falling of the cap, or by knocks. The ball is easily retained in position by the corrugations of the groove which corrugations are protected in the bottom of the groove. The ball always presents a smooth exposed surface 30 and has no protruding parts to become entangled with wrappings and the like, or to injure the fingers in moving it. The corrugations in the groove slightly raise the ball as it moves over these corrugations so that its movement past 35 the index marks can be counted and determined in the dark by the "feel" of the movement. In the assembly of the ball in the groove, the ball is snapped into the groove and the cap is thereby completed. The ball may be applied to the groove 40 at any time before the cap is used which facilitates storage and manufacture.

Having thus described my invention, I claim:

1. A bottle cap comprising a molded body 45 removably attached to and forming a closure for the bottle, an annular undercut groove in said body, an annular row of indexing characters on said body having the same centre as said annular groove, corrugations in said groove corresponding with the location of said indexing characters and 50 a solid metallic ball in said groove of larger diameter than the opening of the groove but smaller

in diameter than the diameter of said groove, and rotatable in the groove and projecting partially above the groove so that the projecting part may be engaged to move it opposite any index character and said ball being held in the located position by said corrugations. 5

2. A bottle cap comprising a molded body removably attached to and forming a closure for the bottle, an annular undercut groove formed in said body, an annular row of indexing characters on said body having the same centre as said annular groove, corrugations in said groove corresponding with the location of the indexing characters, an isolated portion of the wall of said groove, substantially the depth of the groove being reduced in thickness to increase its resiliency and a solid metallic ball larger in diameter than the opening of said groove insertable in said groove opposite the reduced portion of the wall, said ball being smaller in diameter than the diameter of said groove so that it is readily movable in the groove over said corrugations to locate it opposite any index character desired. 10 20

3. An indexing device comprising a body formed of a plastic material with an annular undercut groove having corrugations therein and an annular row of indexing characters having the same centre as said groove, a solid metallic ball in said groove of larger diameter than the opening of the groove and projecting less than one half its height above the groove and being smaller in diameter than the diameter of said groove so that it is free to rotate in the groove, said ball being moved opposite said indexing characters by engaging the projecting part, said corrugations retaining the ball in the position to 25 30 35 which it has been moved.

4. An indexing device comprising a body formed of a plastic material with an annular undercut groove and an annular row of indexing characters having the same centre as said annular groove and corrugations formed in said groove corresponding with said index characters, and a solid metallic ball inserted in said groove of larger 40 diameter than the opening of the groove and 45 partially projecting above the groove and being smaller in diameter than the diameter of said groove so that it is readily rotatable in the groove as it is moved opposite the index character desired. 50
